UNITED STATES PATENT OFFICE.

LAWRENCE E. ROBINSON, OF COFFEYVILLE, KANSAS.

DRY-HOLE PLUG FOR WELLS.

1,092,540.

Specification of Letters Patent.

Patented Apr. 7, 1914.

Application filed April 19, 1913. Serial No. 762,295.

To all whom it may concern:

Be it known that I, LAWRENCE E. ROBINSON, a citizen of the United States, residing at Coffeyville, in the county of Montgomery and State of Kansas, have invented certain new and useful Improvements in Dry-Hole Plugs for Wells, of which the following is a specification, reference being had therein to the accompanying drawing.

10 This invention relates to certain new and useful improvements in dry hole plugs for oil wells; the object being to provide a plug which is formed of a plurality of sections connected together in such a manner that 15 when pressure is brought to bear from above, the sections will be moved in respect to each other in order to increase the diameter of the plug so as to completely fill the well at the point desired.

20 Another object of the invention is to provide a plug which is preferably formed of four tapering staves; two of said staves being connected to a base pin and two to a top pin, which is carried by the stem of the 25 well drilling tool in such a manner that when the bottom of the well is reached, the weight of the stem will move the staves in respect to each other so as to cause the staves to travel upon the inclined faces in 30 order to expand and completely fill the well.

Another object of the invention is to provide the base plug with a packing which is adapted to be expanded by the staves as clearly shown in Figure 2, whereby an exceedingly water-tight joint will be formed in 35 the well in order to prevent any water from rising.

Another and further object of the invention is to provide a plug which is exceedingly simple and cheap in construction; the staves being carried by wooden pins and connected thereto by nails in such a manner that when pressure is brought to bear upon the upper pin, the nails connecting the 45 staves to the pins will be forced out of the pins in order to allow the staves to move in respect to each other so as to expand or increase the diameter of the plug.

Another and still further object of the invention is to provide a plug which is especially adapted to be used for plugging the well at a point where a water stratum is struck in drilling the well, and it is desired to fill up the well to the gas or oil paying stratum, and I have found that by such a

construction of plug, that when set, the moisture will expand the staves so as to wedge the same firmly in position and in connection with the expandable packing, a complete stopper will be formed for the 60 well.

Other and further objects and advantages of the invention will be hereinafter set forth and the novel features thereof defined by the appended claims.

In the drawings—Fig. 1, is a perspective of my improved construction of dry hole plug showing the same in a well before set; Fig. 2, is a side elevation of the plug showing the same expanded to the well; Fig. 3, 70 is a section taken on the line 3—3 of Fig. 2; and Fig. 4, is a perspective showing the construction of the staves forming the body of the plug. Fig. 5, is a perspective view of my improved dry hole plug showing the 75 manner of lowering the plug in the well with a well drilling tool; Fig. 6, is a side elevation of the plug showing my improved construction of lock arranged in position in connection therewith; Fig. 7, is a side elevation of the frangible lock detached; and Fig. 8, is a vertical section through the 80 frangible lock showing the same in position upon the expanding cone.

Like numerals of reference refer to like 85 parts in the several figures of the drawings.

In carrying out my improved invention, I employ a wooden plug which is formed of a plurality of staves 1 herein shown four in number; which are tapered as clearly 90 shown in Fig. 4, and arranged in pairs; one pair having its narrowest ends arranged reverse to the other pair as clearly shown in Fig. 4. The side edges of these staves are beveled so as to snugly fit one another and form a complete cylinder, and it will be seen that by shifting or moving one pair of staves longitudinally in respect to the other, the diameter of the cylinder formed by the staves will be increased so as to expand the 95 plug within the well, as will be later described.

One pair of the staves are carried by a base plug 2 and secured thereto by nails or fastening members 3, and the other pair of staves are connected to a top pin 4 by nails or fastening means 5; the lower ends of this pair of staves also being secured to the pin 2 by nails or fastenings as shown at 6. The pins 2 and 4 are provided with heads 7 110

and 8 and in Fig. 1, I have shown the staves connected to the pins 2 and 4 in position to be lowered into the well, and it will be seen that by forcing the pins 2 and 4 toward each other, the fastenings for holding the staves in the position shown, will be forced out of position and the inclined faces of the plugs will travel one upon the other so as to increase the diameter of the plug.

In order to form an exceedingly tight joint at the lower end of the plug, I provide the pin 2 with an expansible packing 9 which is preferably putty wrapped with tape in order to hold the same in position thereon which is adapted to be engaged by the staves when forced into position as shown in Fig. 2, so as to force the packing 9 outwardly around the end of the staves. By forming the staves wedge-shape or tapering and by arranging the staves alternately in the form of a circle, the inclined faces of the abutting staves will ride upon one another when forced longitudinally in order to increase the diameter of the circle so as to expand the staves tightly within the casing of the well.

In order to provide means for lowering and setting the plug within the well casing, I provide the head 8 of the pin 4 with a tapering stem 10 which is adapted to be forced into the threaded socket 11 of the stem 12 of the well drilling tool, which is preferably about forty feet in length, and is carried by a cable 13; and it will be seen that in forcing the stem into the threaded socket 11 it will cut its own thread in the stem in such a manner as to hold the same firmly in position when being lowered in the well, and by the weight of the stem of the well drilling tool against the head 8, the staves carried by the pin 4 will be forced downwardly over the pin 2 until the head 8 engages the other pair of staves, when the whole set of staves will move in a body against the packing 9 and expand the same outwardly so as to completely stop the well at the desired point. The head of the base pin 2 is adapted to rest on the bottom of the well, and it will be seen that the weight of the stem 12 of the well drilling tool will be sufficient to disengage the staves from the base pin so as to allow the same to move longitudinally in respect to each other, whereby they will be expanded or in other words, the diameter of the plug will be increased as the staves move longitudinally in respect to each other so as to expand the plug tightly against the well casing and by the moisture, the staves which are formed of wood, will swell and completely close the casing.

After the plug has been set in the casing or well, the stem of the well drilling tool is drawn upwardly and in most cases, the upper pin will remain within the staves, but

in some cases, the upper pin will be drawn out with the stem of the well drilling tool, but I have found that it is not essential for the upper pin to remain in position within the staves and therefore, the operation of the plug is not affected by the pin 4. The complete plug is formed of wood including the pins, and is subjected to the swelling action of water so as to wedge the same firmly in position and in connection with the packing carried thereby, a complete stopper is formed which has many advantages over other classes of dry hole plugs now in use.

In order to provide means for rigidly locking the plug in position within the well after the same has been set so as to resist exceedingly high pressure, I provide a lock which is adapted to be used in connection with the plug and comprises a conical member 14 over which is arranged a frangible cast-iron member 15 which is preferably formed cylindrical in shape having its lower portion divided into segments 16 which are connected at their upper ends by a frangible cap 17; said segments being provided with tapering inner faces 18 forming a conical opening to receive the conical member 14. The outer faces of the segments 16 are serrated to form teeth so arranged that when the cap 17 is broken in order to allow the segments to be expanded by the expanding member 14, they will be forced outwardly and embed themselves in the side of the well or the casing as the case may be, and securely lock the plug from moving upwardly.

In setting the lock, the same is dropped into the well after the plug has been set and by the impact of the member 14 striking the stem 10 the segments will be slightly spread, and in some instances the frangible cap will be broken. When the locking device is in this position upon the plug, a well drilling tool is dropped down into the well so that the impact against the cap will cause the same to break allowing the segments 16 to expand by riding upon the inclined faces of the expanding member and by delivering a number of blows upon the cap with the well drilling tool, the serrated faces will be embedded in the side of the well or casing as clearly shown in Fig. 6, thereby making it impossible for the expansible plug to be moved upwardly by pressure of the sand or water.

While I have shown and described a locking device to be used in connection with the plug, it is of course understood that the plug can be used without the locking device but by combining the two as shown, an exceedingly practical means is provided for maintaining the plug in a set position.

From the foregoing description, it will be seen that I have provided a plug formed of a plurality of staves so constructed that

when moved in respect to each other, the diameter of the plug will be increased so as to expand the plug into the casing to completely close the same.

5 5 I claim:

1. A plug for oil wells comprising a body formed of a plurality of tapering staves having contacting side edges.

10 2. A plug for oil wells comprising a body formed of a plurality of tapering staves arranged in pairs having contacting side edges, and means for moving said staves longitudinally in respect to each other.

15 3. An expansible, cylindrical plug for oil wells, formed of a plurality of tapering staves having contacting side edges slidably mounted in respect to each other.

20 4. A plug for oil wells comprising a body formed of a plurality of tapering staves, headed pins detachably carried by said staves, and means for forcing said pins together for expanding said staves.

25 5. A plug for oil wells comprising a bottom pin and a top pin, staves connected to said pins, and a packing carried by the bottom pin adapted to be expanded by said staves.

30 6. A plug for wells comprising a headed pin having a plurality of oppositely arranged tapering staves temporarily connected thereto and arranged in pairs, and means carried by one pair of staves for moving said staves longitudinally in respect to each other.

35 7. The combination with a pin provided with a stem, of tapering staves carried by said pin, a second pin carried by said staves and connected to the staves, said second pin having an expansible packing adapted to be engaged by said staves.

40 8. An expansible plug for wells comprising a plurality of tapering staves alternately arranged in the form of a circle having contacting side edges, and means for moving said staves longitudinally in respect to each other for increasing the diameter of the circle formed by said staves.

45 9. A plug comprising a headed base pin, tapering staves carried by said base pin, an expansible packing carried by said pin, a top pin carried by two of said staves, and

means for attaching said top pin to the stem of a well drilling tool.

10 55 An expansible plug for wells comprising a base pin and a top pin having contacting side edges, staves carried by the base pin, and means for moving two of said staves longitudinally in respect to the other staves.

11 60 A plug for oil wells comprising a base pin having a head, an expansible plastic packing arranged on said pin against said head, and a sectional body carried by said pin adapted to expand said packing.

12 65 A plug for oil wells comprising a base pin carrying a plastic packing, and a body slidably mounted on said pin for expanding said packing.

13 70 A plug for wells formed of a plurality of tapering staves slidably mounted in respect to each other having contacting side edges, and means for moving said staves longitudinally in respect to each other.

14 75 A plug for oil wells comprising a cylindrical body formed of a plurality of tapering staves arranged in pairs, having contacting side edges, the larger end of one pair of staves being reverse to the larger end of the other pair of staves, and means for moving said staves longitudinally in respect to each other.

15 80 A plug for wells comprising a base pin, a body formed of a plurality of tapering staves detachably carried by said pin, and a second pin connected to two of said 85 staves for moving said staves longitudinally in respect to the other staves.

16 85 An expansible wooden plug for wells comprising a cylindrical body formed of a plurality of tapering staves having contacting side edges, one pair of staves being arranged in the plane above the other pair of staves, and means for moving said staves longitudinally in respect to each other for increasing the diameter of the body formed 90 by said staves.

In testimony whereof I affix my signature in presence of two witnesses.

LAWRENCE E. ROBINSON.
